REMOVABLE DENTURE

Robert J. Maniola, deceased, late of Chicago, Ill.,
by James J. Maniola, administrator, Chicago,
Ill., assignor to James J. Maniola, Chicago, Ill.

Application April 26, 1947, Serial No. 744,205

9 Claims. (Cl. 32—5)

1

This invention relates to improvements in removable dentures.

One object of the invention is to provide improved dentures which utilize the natural undercutts of the abutment teeth for retaining the denture in proper position but having parts so formed that the dentures can readily be placed in position or removed for cleansing.

Another object of the invention is to provide a denture which is adapted to seat in an edentulous area defined by natural undercut mesial and distal surfaces of the abutment teeth and which avoids the formation of objectionable food traps or cavities by closing all the interproximal spaces spanned by the denture.

An additional object of the invention is to provide a denture of two cooperating parts which are separately insertable into the edentulous area or space for which they were made and to be releasably latched together while in said space and which, while in said space, closely contact the mesial and distal surfaces of the abutment teeth for retention in position against vertical and lateral displacement.

Other objects of the invention relate to various features of construction which will be apparent from a consideration of the following specification and accompanying drawings, wherein

Figure 1 is a broken lower plan view of a set of upper teeth showing an improved denture in position;

Fig. 2 is an elevation of the teeth of Fig. 1 as viewed from a position indicated by line 2—2 of Fig. 1 and showing an artificial denture in place;

Fig. 3 is a view similar to Fig. 2 but illustrating the denture in position in dotted lines and in a removed position in full lines;

Fig. 4 is a broken enlarged buccal view of the denture in longitudinal section and showing the relation thereof to the two abutment teeth;

Fig. 5 is a sectional view taken on line 5—5 of Fig. 4;

Fig. 6 is a perspective view of the two sections of which the improved denture is formed, the sections as shown being separated and inverted;

Fig. 7 is a view similar to Fig. 4 but illustrating a modified relationship between one denture section and the contiguous abutment tooth.

In the drawings, a set of natural upper teeth are shown, two of which have been replaced by a removable denture that is illustrative of the present invention. The two natural teeth that have been removed are the second right bi-cuspid and the first molar. Hence, the abutment teeth for the edentulous area caused by the removal of

2

the two natural teeth are the first right bi-cuspid 10 and the second right molar 11. As indicated in Fig. 2, the distal surface of tooth 10 and the mesial surface tooth 11 are undercut surfaces, that is, each converges generally toward the root tip of the respective tooth. These undercut surfaces mentioned result from the fact that the abutment teeth, as illustrated, are broader at the outer portions than at the gum-line. These undercut surfaces have been a source of trouble in making conventional removable partial dentures that avoid the formation of food traps, but such undercut surfaces are utilized in the present improvements for retention of the dentures in place and without the use of bars and clips of the types that heretofore commonly have been used.

The denture illustrated in Figs. 1 to 6 comprises two coacting separable sections A and B which are insertable in the edentulous area in the order named and are removable in the reverse order. Fig. 6 illustrates the sections A and B as viewed from the right in Fig. 1, that is the lingual side, and also shows the sections in inverted relation, Fig. 1 being a view of the upper teeth. The section A is a casting of metal or a moulding of appropriate plastic and comprises a surface 12 saddle-shaped in accordance with the gum surface or ridge portion over which it is to be worn, as indicated in Fig. 5. The body 13 of section A has formed thereon a latching member 14, preferably on the lingual side of the section, which cooperates with a mating latch member of section B for releasably retaining the members in co-operative relation as will be later described. Extending upwardly from the body 13 is a vertical portion or pillar 15 provided with a wall or surface 16 that is molded or cast to conform to the mesial surface 17 of the abutment tooth 11. Hence, the wall 16 is not only curved in horizontal cross-section generally to conform to the shape of the mesial surface of the tooth 11 with which the surface 16 contacts, but it is inclined from the vertical reciprocally with respect to the undercut mesial surface of the tooth 11. In Fig. 4 the relation of the surface 16 of the section A to the mesial undercut surface 17 of tooth 11 is clearly indicated.

The pillar 15 is provided with a rearwardly, that is, distally, directed lug 18 adapted to seat in a recess that may be ground, if necessary, in the occlusal surface of the tooth 11 as indicated at 19 in Fig. 4. The forward or mesial surface 20 of the pillar 15 is disposed in a plane that is parallel to the medial line of the undercut distal surface 21 of the abutment tooth 10 as indicated

in Fig. 4. Hence when the section A of the improved denture has been placed in position in the edentulous space, the two surfaces 20 and 21 being parallel will accommodate insertion of the section B in a direction parallel with the medial lines of the surfaces 20 and 21 as will be more fully described hereinafter.

Again referring to Fig. 6, it will be seen that the section B carries the artificial teeth 22 and 23 which replace the natural teeth above mentioned. As stated, the plate of section B, as shown in Fig. 5, has its gum contacting surface 24 shaped in conformity with the contour of the portion of the gum ridge over which it is to seat. The mesial surface 25 of the section B is inclined complementary with respect to the undercut distal surface 21 of the tooth 10 and transversely corresponds to the transverse curvature or contour of the tooth while the distal end of section B has a surface section 26 that is inclined for contact with the surface 20 of section A. The mesial end portion of the section B, as shown, also is provided with a lug 27, that extends mesially onto a seat 28, ground if necessary, in an occlusal surface of the abutment tooth 10 as indicated in Fig. 4.

The artificial teeth 22 and 23 are secured to the section B by any approved means, such as by pins or studs 29 formed integrally with the section in the casting or moulding thereof and which enter recesses 30 provided in the teeth. Cement retains the teeth in proper relation.

The surface 24 of the section B is shaped, as stated, to conform to the respective gum surface except that at the distal end of such surface it is relieved, as at 31, as indicated in Figs. 4 and 5, for fitting over the upper portion of the body 13 of section A whereby the two upper surfaces of sections A and B provide substantially a continuous ridge-contacting and ridge-conforming surface when the sections are in operative position. The lower lingual portion of section B, distally considered, is provided with a latch portion 32 comprising a groove or channel 33 whereby when the sections have been moved into final seating position in the edentulous area, will engage the latch portion 14 of section A for latching the sections together. As will be noted in Fig. 5, the relieved portion of the gum contacting surface of the section B is defined by a wall 34 that preferably is inclined or undercut slightly for firmly-engaging the complementary or mating wall 35 of the section A whereby the latch portion 32, which is made sufficiently thin to render it adequately resilient, may be sprung slightly under the camming action of the rib-like latch portion 14, to cause the groove 33 to snap over the rib 14 and so releasably retain the denture sections in position.

As will be apparent from the foregoing, the sections A and B are moulded or cast to fit the edentulous area of a particular patient and hence all sections A and B of the improvements will not be of the precise shape shown in the drawings nor will the angles and cross sectional shapes of the distal and mesial surfaces of the denture be precisely as illustrated. The distal and mesial surfaces of the abutment teeth however, or at least one of such surfaces, must be of an undercut form for taking full advantage of the present improvements.

In placing the sections A and B into operative position, the section A is first placed in the edentulous space with the lug 18 upon the seat 19 and with the wall 16 contacting the mesial

wall 17 of the tooth 11. The section B is next placed in position and may be moved into proper position in a direction parallel to the plane of the surface 20 and to the medial line of surface 21 since, as above described, such surface and line are parallel and surfaces 25 and 26 likewise are of similar parallelism, that is, they form the same angles to the vertical. The lug 27 of section B is positioned upon its seat 28 and the walls 34 and 35 of the sections are inter-engaged whereupon slight pressure upon the resilient latch section 32 of section B causes the latch members (in the particular form shown comprising the rib 14 and the cooperating groove 33), to snap relatively into engagement. In pressing the section B into position, the wedging action of the inclined surface 26 of section B on the reciprocally inclined surface 20 of section A tends to urge the sections longitudinally in opposite directions and thereby effect close inter-engagement of the surfaces 16 and 17 and 21 and 25, respectively.

The lugs 18 and 27 receive the gum-wise thrust of the teeth 22 and 23 in biting or chewing and thus relieve the gum ridges from excessive pressure. The lugs also restrain rocking movement of the denture with respect to the ridge of the gums as an axis, and cooperate with the arcuate, gum fitting lower surfaces 12 and 24 of the sections A and B, as well as with the arcuate shape 30 of the mesial and distal surfaces of the denture (which closely contact the respective surfaces of the abutment teeth) in inhibiting lateral displacement of the denture, that is lingually or buccally. The movement of the denture in a vertical direction, that is, away from the gum surface on which the denture fits, is restrained by the coaction of the end walls 16 and 25 of the sections A and B with the respective contacting undercut walls of the abutment teeth. Hence when the denture sections have been placed in position in the edentulous area and latched together, they are retained against vertical displacement by the wedging or key-stone action described. The denture can be removed readily first by lifting up on the latch portion 32 of section B and thereupon removing section B and then section A.

Fig. 7 illustrates the adaptation of the structure shown in Figs. 1 to 6 inclusive to an edentulous area having but one undercut tooth surface, indicated at 17'. The opposite end of the area is defined by an abutment tooth 10' having a vertical surface 36. The denture shown in Fig. 7 is in all respects similar to the denture above described except as modified for coaction with the tooth indicated as 10' which has a vertical rather than an undercut surface. The cooperating surface 37 of the denture section B' conforms to the surface 36. Assuming that the denture sections are latched together as described in connection with the form shown in Figs. 1 to 6, the denture of Fig. 7 will not move vertically by gravity (assuming it is an upper denture) since any vertical movement would cause the undercut surface 17' of tooth 11' to effect a wedging action on the complementary surface 16' of the section A', the component of which would tend to force the denture to the right as viewed in Fig. 7. Such movement, however, is resisted by the abutment tooth 10'. Likewise the right hand end of the denture shown in Fig. 7 cannot swing downwardly about the lug 18' of section A' as a pivot for the reason that no clearance for such arcuate movement is present within the edentulous area.

It will be obvious that the dentures embodying the invention shown and described are adapted

for use as lower dentures as well as upper dentures and that the relative arrangement of sections A and B may be reversed. Also it will be seen that a section, such as section B, may be provided with more than two teeth where the edentulous area requires a greater number of teeth than those shown, or with a single tooth. It will also be apparent that the improved denture, comprising the two sections A and B arranged in end to end relation, is retained as a unit against vertical displacement by reason of the keying action between the respective contiguous surfaces of the abutment teeth and the remote ends 16 and 25 of the sections which are reciprocally or complementarily shaped to conform to or mate with the respective surfaces of the teeth. It will also be apparent that slight movement of the sections A and B in axial directions may occur as section B is pressed into firm position in the edentulous spaces due to the coaction of the reciprocally shaped inclined surfaces 20 and 26 which tends to move the sections in opposite directions against the respective teeth 10 and 11. The close fitting relationship of the remote end portions of the denture and the abutment teeth avoids the formation of food traps or cavities between the abutment teeth and the adjacent artificial teeth since the respective interproximal spaces are closed by the adjacent portions of the denture sections A and B. Likewise, since the inclined surfaces 20 and 26 are reciprocally formed, they closely interfit and exclude food particles from between the same and since they are retained in such interfitting relation by the latching means they, in turn, retain the remote ends of the sections in close contact with the abutment teeth.

While removable dentures have been shown and described that are illustrative of the invention, various changes in the details shown may be made within the spirit of the invention.

What is claimed is:

1. A removable denture for use in an edentulous space defined by undercut walls of two abutment teeth comprising a pair of denture sections adapted to be positioned consecutively in said space and each provided with a remote end wall reciprocally shaped with respect to and adapted to contact one of the undercut surfaces of the respective teeth, said sections being provided with reciprocally shaped interfitting adjacent surfaces a portion of each of which surfaces is disposed at an angle at least as great as the angle of the undercut wall of the second abutment tooth and adapted to urge the sections in opposite directions as the second of said sections is pressed into interfitting relation with the first section within said space for thereby urging said remote end walls into contact with the said surfaces of the respective teeth for restraining vertical movement of the denture from said space, and means releasably securing said adjacent ends of the sections in said interfitting relation.

2. A removable denture for use in an edentulous space defined by undercut walls of two abutment teeth comprising a pair of denture sections adapted to be positioned consecutively in said space and each provided with a remote end wall reciprocally shaped with respect to and adapted to contact one of the undercut surfaces of the respective teeth, said sections being provided with reciprocally shaped interfitting adjacent surfaces a portion of each of which surfaces is disposed at an angle at least as great as the angle of the undercut wall of the second abut-

ment tooth and adapted to urge the sections in opposite directions as the second of said sections is pressed into interfitting relation with the first section within said space for thereby urging said remote end walls into contact with the said surfaces of the respective teeth for restraining vertical movement of the denture from said space, and cooperating snap action latch portions on said sections for releasably retaining the adjacent ends of said sections in said interfitting relation.

3. A removable denture for use in an edentulous space defined by undercut walls of two abutment teeth comprising a pair of denture sections adapted to be positioned consecutively in said space in end-to-end relation, the remote ends of said sections being shaped reciprocally with respect to the respective undercut walls, the other ends of said sections having reciprocally shaped surfaces disposed in reciprocally inclined planes for interfitting contact upon the positioning of said sections in said space with said remote ends in contact with said walls, and releasable means for securing said adjacent surfaces of the sections in interfitting contact and retaining said remote ends in contact with said walls whereby said remote ends restrain vertical displacement of the denture from said space.

4. A removable denture for use in an edentulous space defined by undercut walls of two abutment teeth comprising a pair of denture sections adapted to be inserted consecutively in said space, the first insertable section having a tooth contacting end wall reciprocally shaped for contact with the undercut wall of one of said teeth and having an opposite end portion providing a surface disposed at an angle parallel to the angle of the undercut portion of the other abutment tooth, said second insertable section having an end wall shaped reciprocally with respect to the undercut wall of the latter tooth for contacting the same and having an opposite end wall portion providing a surface shaped for interfitting contact with said surface of the first section and disposed in a plane parallel to the plane of said surface of the first section and adapted to contact the same when the sections are in position in said space, and means for releasably retaining said surfaces of the sections in contact for retaining the said tooth-contacting ends of the respective sections in engagement with the undercut walls of the respective abutment teeth.

5. A removable denture for use in an edentulous space defined by undercut walls of two abutment teeth comprising a pair of separable sections insertable consecutively in end-to-end relation in said space, the first insertable section having an end wall reciprocally shaped for contact with the undercut wall of one of said teeth, the second insertable section having an end wall shaped reciprocally for contact with the undercut wall of the second tooth, the other end portions of the sections having cooperating inclined surfaces reciprocally shaped for interfitting contact when the sections are in position in said space and being arranged in planes enabling said second section to be inserted in said space in a direction paralleling the plane of the undercut wall of said second tooth.

6. A removable denture for use in an edentulous space defined by undercut walls of two abutment teeth comprising a pair of separable sections insertable consecutively in end-to-end relation in said space, the first insertable section having an end wall reciprocally shaped for contact with the undercut wall of one of said teeth,

the second insertable section having an end wall shaped reciprocally for contact with the undercut wall of the second tooth, the other end portions of the sections providing cooperating surfaces reciprocally shaped for interfitting contact when the sections are in position in said space and being arranged in inclined planes enabling said second section to be inserted in the space in a direction paralleling the plane of the undercut wall of said second tooth, and means for releasably latching said sections together in said end-to-end relation.

7. A removable denture for use in an edentulous space defined by undercut walls of two abutment teeth comprising a pair of separable sections insertable consecutively in end-to-end relation in said space, the first insertable section having an end wall reciprocally shaped for contact with the undercut wall of one of said teeth, the second insertable section having an end wall shaped reciprocally for contact with the undercut wall of the second tooth, the other ends of the sections having cooperating surfaces reciprocally shaped for interfitting contact when the sections are in position in said space and arranged in planes inclined at an angle at least as great as the angle of the undercut wall of said second abutment tooth for enabling said second section to be inserted in the space in a direction paralleling the plane of the undercut wall of said second tooth, and cooperative latching elements on the lingual sides of said sections for releasably latching the sections in end-to-end relation in said space.

8. A removable denture for use in an edentulous space defined by undercut walls of two abutment teeth comprising a pair of separable sections insertable consecutively in end-to-end relation in said space, the first insertable section having an end wall reciprocally shaped for contact with the undercut wall of one of said teeth, the second insertable section having an end wall shaped reciprocally for contact with the undercut wall of the second tooth, the other ends of the sections having cooperating inclined surfaces reciprocally shaped for interfitting contact when the sections are in position in said space and being arranged in planes enabling said second section to be inserted in the space in a direction paralleling the plane of the undercut wall of

50

said second tooth, and a pair of releasable latching elements on the lingual side of said sections comprising a rib on one section and a flexible portion of the other section provided with a receiving recess arranged for snap-engagement with said rib.

9. A removable denture for use in an edentulous space between two abutment teeth one of which has an undercut abutment wall and the other of which has a vertical abutment wall, said denture comprising a pair of sections adapted to be inserted consecutively in end to end relation in said space and of a combined length to fill said space, the first insertable section being provided with an end wall reciprocably shaped for contact with the undercut wall of the first said tooth, said second insertable section being provided with an end wall reciprocably shaped for contact with the abutment wall of the second abutment tooth, the other ends of said sections having cooperating parallel surfaces reciprocally shaped for interfitting contact when the sections are in position in said space and being arranged at an angle convergent with respect to the abutment wall of said second tooth in the direction of the root of the tooth for enabling the second section to be inserted in position in a direction paralleling the plane of the abutment wall of said second tooth and cooperating to exert endwise thrusts on the sections as the second section is inserted in position thereby pressing the end walls of the sections into contact with the respective abutment walls of the teeth, and means for releasably latching the contacting parallel surfaces of the section together.
